CATHEAD

Philip M. Rea, Oklahoma City, Okla.

Application February 20, 1937, Serial No. 126,841

7 Claims. (Cl. 254—173)

This invention relates to cat-heads used in connection with the draw-works of a well drilling rig for providing the power required in breaking the tool joints in a string of drill pipe or the like.

The principal object of the invention is to provide a cat-head with a simple and reliable means for effecting operative connection and disengagement of the driven element with the counter-shaft of the draw-works.

It is also an important object of the invention to provide a cat-head construction which permits of ready assembly and secure retention of the parts.

Further objects of the invention are to provide an improved means for manually effecting engagement of the latch-dog with a driven quill about which the driven element of the cat-head is rotatably mounted; to provide a cat-head construction whereby the driving forces are exerted in the direction of rotation so that there are no end thrusts imparted to the driving and driven elements; and to provide for engaging and tripping of the latch-dog without resultant ill effects on the draw-works.

In accomplishing these and other objects of the invention, as hereinafter pointed out, I have provided improved details of structure, the preferred form of which is illustrated in the accompanying drawings, wherein:

Fig. 1 is a perspective view of a portion of a draw-works equipped with a cat-head embodying the features of the present invention.

Fig. 2 is an enlarged detail section through the cat-head illustrating driving engagement of the latch-dog with the driving quill.

Fig. 3 is a vertical section through the cat-head on the line 3—3 of Fig. 2, illustrating the latch-dog in disengaged position but ready to be moved into position to be engaged by a latch-dog engaging face of the quill.

Fig. 4 is a similar section showing the latch-dog in engaged position and moving toward the point where the latch-dog is ordinarily disengaged from the quill.

Fig. 5 is a section on the line 5—5 of Fig. 2 illustrating the latch-dog control rollers entering the return track to hold the latch-dog out of driven engagement with the quill during reverse rotation of the driven element.

Fig. 6 is a detail view of the latch-dog, one of the control rollers being shown in section.

Fig. 7 is a detail perspective view of the housing sections shown in disassembled spaced relation to better illustrate the track-ways therein.

Fig. 8 is a detail perspective view of the driving quill, the driven element, the latch-dog and the spool which cooperates with the quill in retaining the driven element.

Referring more in detail to the drawings:

1 designates a draw-works including jack posts 2 mounted on a derrick platform 3 and supporting the usual counter-shaft 4 and line shaft 5 from which the rotary drilling tools are operated as in conventional practice. The end of the line shaft 5 projects beyond the outer post 2 to mount a cat-head 6 which is constructed in accordance with the present invention.

The cat-head includes a quill 7 having a sleeve-like body 8 provided with a longitudinal bore 15 9 to snugly engage the projecting end of the shaft 5. The quill is keyed to the shaft 5 by means of a spline 10 engaging in a keyway 11 formed in the side of the shaft and in a registering key recess 12 that is formed in the inner 20 face of the sleeve-like body, as best shown in Figs. 2 and 3. The quill is of sufficient length to accommodate a driven element 14 which operates a jerk line presently described and to mount a spool 15 that is used in certain of the drilling 25 operations and which cooperates with the quill in retaining the driven element. The outer periphery of the quill is shaped to provide an annular stop flange 16 on the end adjacent the post 2, and spaced from the stop flange a distance corresponding to the width of the driven 30 element is an annular shoulder 17 that is formed by reducing the outer diameter of the quill to correspond to the inner diameter of the spool.

Formed in the outer surface of the quill, at a point midway between the flange 16 and the shoulder 17, is a series of arcuate recesses or grooves 18 having bottoms 19 extending from a point on the periphery of the quill to a spaced point inset from the surface of the quill to provide a latch-dog engaging face 20. The side walls 21 and 22 of the recesses extend substantially parallel and are spaced apart a distance slightly greater than the width of the latch-dog, later described.

The driven element includes a collar 23 having a central internal band 24 of a diameter to freely and rotatably engage the notched portion of the quill and having its ends counter-bored to provide annular bearing recesses 25 and 26 50 in which are mounted sets of roller bearings 27 and 28 to reduce tendency of the collar to drag upon the quill when the collar is disengaged from driving relation therewith as later described. The outer periphery of the bushing is provided 55

with an annular groove 29 separating annular bearing faces 30 and 31 which engage in bushings 32 and 33 located within the sections 34 and 35 of a housing 36.

5 Formed in the groove 29 and extending completely through the wall of the collar 23 is a slot 37 in which a latch-dog 38 is adapted for movement as later described. The slot 37 includes a portion 39 of slightly greater width than the 10 groove 29 to allow free movement of the latch-dog lug. The latch-dog is best illustrated in Fig. 8 and includes a substantially rectangular lug portion 40 that extends freely through the portion 39 of the slot 37 and is adapted to engage 15 in the respective notches of the quill to effect driving engagement with the faces 29 as later described. The latch-dog includes a tail portion 41 pivotally mounted within the narrow portion of the slot 37 on a pivot pin 42 that extends 20 through an opening 43 in the tail portion of the latch-dog and has its ends mounted in openings 44 formed in the sides of the slot 37 as best illustrated in Fig. 8.

Carried by the latch-dog at a point directly 25 above the lug 40, are laterally extending spindles 45 and 46 carrying rollers 47 and 48. Formed in the latch-dog is a tapered socket 49 in which one end of a jerk line 50 is babbitted as shown at 51 in Fig. 4. The jerk line extends over the tail 30 portion of the latch-dog and operates within the groove 29. Its opposite end is adapted to be connected with a wrench on the upper section of a tool joint (not shown) as in well known practice.

35 The housing sections 34 and 35 are of substantially the same construction and include annular web or disk-like wall portions 52 and 53 having axial openings 54 and 55 of suitable diameter to pass freely over the quill and to accommodate the bushings 32 and 33, previously mentioned. Formed in the web portions 52 and 53, in concentric relation with the bushed openings, are inner and outer arcuate track-ways 56-57 and 58-59 which are connected at their respective ends by transfer grooves 60-61 and 62-63 respectively. The inner groove conforms in width to the diameter of the rollers 47 and 48 on the latch-dog and are of a depth to freely accommodate the length of the rollers. The outer grooves are of similar depth but may be of greater width than the diameter of the rollers as shown in Fig. 5. The track-ways are thus separated by arcuate flanges 64 and 65 having inner edges 66 and 67 spaced apart to form an annular pathway through which the latch-dog is adapted to move as later described. The ends 68-69 and 70-71 of the flanges are slightly rounded at their juncture with the track-ways to facilitate transfer of the rollers from one 55 groove to the other. The transfer grooves 61 and 63 are rounded, as at 72 and 73, to provide throw-out portions at the terminal ends of the inner track-ways to guide the rollers into the outer track-way for return of the driven collar under pull of the jerk line as later described.

65 In order to transfer the rollers from the outer groove to the inner groove, and thereby effect engagement of the lug 40 with one of the recesses of the quill, I provide an elevating device including a lever 74 extending through slots 75 and 76 provided in the outer annular flange of the housing sections as best shown in Fig. 7. The lever is pivoted on a pin 77 that is carried by spaced ears 78 and 79 on the respective housing 70 sections. The inner end 80 of the lever projects

a sufficient distance within the housing to adapt it for movement entirely across the width of the outer track-ways and slightly within the space at the ends 69 of the flanges 64 and 65, as shown in Figs. 4 and 5. The outer end 81 of the lever 5 is connected with a control line 82 whereby the lever may be actuated to effect transfer of the rollers on the dog from the outer track to the inner track and thereby move the lug into position to be engaged by one of the latch engaging 10 faces of the quill. The outer flanges are of sufficient depth to close the space circumferentially of the latch-dog passage, however, the portions thereof adjacent and between the terminal ends of the track-ways are notched as at 83 and 84 15 to provide a slot through which the jerk line is passed, as clearly shown in Figs. 1, 3 and 4, for connection with the wrench as above mentioned.

The housing sections are provided with pairs of radial lugs 85 and 86 through which fastening devices, such as bolts 87, are extended to secure the sections together. The section 34 has an attaching flange 88 whereby the housing is secured to the post 2 to prevent rotation thereof.

20 The spool 15 includes a sleeve-like body 89 25 having an inner diameter to pass over the reduced portion of the quill as shown in Fig. 2, and is keyed thereto by a spline 90 engaged in registering grooves formed within the outer periphery of the quill and in the inner diameter of the 30 spool. The spool has an annular flange 91 abutting the annular shoulder 17 and which cooperates with the flange 16 to retain the roller bearings as shown in Fig. 2. In order to prevent lateral displacement of the spool, the outer end 92 35 is recessed to accommodate a plate 93 that is secured to the end of the quill by fastening devices, such as cap screws 94, extending through openings 95 in the plate and into threaded sockets formed in the end of the quill as shown in 40 Fig. 8.

45 In assembling a cat-head constructed as described, the key 10 is inserted in the recess 12 of the quill and the quill is slid over the projecting end of the shaft 5 so that the key enters the 45 groove of the shaft. The housing section 34 is then sleeved over the quill so that the outer face of the web portion thereof engages the flange 16. The driven element carrying the latch-dog is then sleeved over the quill and the roller bearings 50 inserted in the bearing recesses 25 and 26. When the driven element is properly assembled, the annular bearing portion 39 thereof engages within the bushing of the housing section 34 so that it is rotatably mounted therein. The jerk line is 55 extended around the driven element so that it lies within the groove 29. The roller 47 is located in the transfer groove 60 of the housing section 34, for example as shown in Fig. 3. The other housing section is then sleeved over the bearing 60 portion 31 of the driven element whereupon the bolts 87 are passed through the ears 75 and 86 to secure the sections together. The flange 88 of the section 34 is then attached to the post 2 to prevent relative rotative movement of the housing. The lever 74 is then applied so that the inner end thereof engages under the latch-dog as shown in Fig. 3, and connected with the control line 82. The spool is then sleeved over the outer end of the quill after which the key 90 is inserted 70 to secure the spool in driving relation therewith. After insertion of the key the plate 93 is applied to the end of the quill to complete the assembly.

75 In using a cat-head assembled as described, the normal position of the latch-dog is as illustrated

in Fig. 3, with the head of the latch-dog resting upon the forward end 80 of the lever 74, and with the rollers located in the transfer passages 62. In this position the lug on the latch-dog is out of 5 the path of travel of the latch engaging faces 20. The quill therefore rotates freely within the driven element and the driven element remains stationary due to the fact that the friction of the surfaces 30 and 31 with the housing bushings 10 is great enough to resist any tendency for the driven element to rotate. Movement of the driven element is also resisted by the jerk line. After the jerk line has been connected with the wrench used in breaking the tool joint, the latch-dog is rendered effective by pulling on the cable 82 to cause 15 the forward end of the lever 74 to raise the latch-dog into position where the rollers 47 and 48 will enter the inner track-ways. In this position the lug on the latch-dog is moved into peripheral contact with the quill and into one of 20 the recesses to be engaged by the latch-dog engaging face 20. The quill therefore picks up the driven member through its connection with the latch-dog, causing it to rotate in a counter-clockwise direction, Fig. 3. Rotation of the driven element causes the jerk line to wrap about the periphery of the groove 29 as shown in Fig. 4 to exert a pull on the wrench. The rollers 47 and 48, moving in the inner cam groove, keep 25 the lug of the latch-dog in engagement with the quill so that the clutching engagement is maintained until the rollers engage the rounded portions 73 of the transfer grooves 61 and 63. As soon as the rollers engage these portions of the 30 grooves, they are cammed outwardly to lift the lug out of engagement with the quill and to guide the rollers into alignment with the outer track-ways, as shown in Fig. 5. When a pull is exerted on the jerk line, the driven member is caused to 35 rotate in a clockwise direction (Fig. 5), so that it is returned to its starting point, as illustrated in Fig. 3. Due to the fact that the rollers remain in the outer track-ways the latch-dog is held out 40 of driving engagement with the quill. As soon as 45 the rollers contact the lever 74, they cause the forward end of the lever to swing downwardly, restoring the lever to its original position so that the latch-dog can be again lifted thereby into engagement with the driving portions of the 50 quill.

From the foregoing it is obvious that I have provided a cat-head construction whereby the driving forces are all exerted in the direction of rotation so that there are no end thrusts imparted to the driving or driven elements. The engagement of the latch-dog with the quill, and also the tripping of the latch-dog from engagement with the quill, are accomplished without shock and resultant ill effects on the draw-works. 55 The pull on the line is also applied directly into the shaft and at a point close to the shaft support on the draw-works.

What I claim and desire to secure by Letters Patent is:

60 1. In combination with a rotatable driving member having latch-dog engaging portions and bearing races on the respective sides of said engaging portions, a driven member including a collar rotatably mounted on the driving member and having races cooperating with the first named races, antifriction bearings for said races, a latch-dog movably supported on the driven member and adapted to engage the latch engaging portions on the driving member, a housing for said 65 driven member, means in the housing forming

communicating primary and return trackways, means for automatically shifting the latch-dog from the primary to the return track-way and disengaging the dog from the driving member, and manually operable means at the opposite end 5 of the track-ways for returning the latch-dog to the primary track-way and engaging said dog with the driving member.

2. In combination with a rotatable driving member having latch-dog engaging portions, a 10 driven member including a sleeve-like body rotatably mounted on the driving member, a latch-dog movably supported on the driven member and adapted to engage the latch engaging portions on the driving member, a housing for said driven member and having inner and outer track-ways interconnected by transfer-ways, guide means on the latch-dog operable in said ways to respectively maintain engagement of the latch-dog with the driving member during rotation of the driven 15 member by the driving member and disengagement of the latch-dog upon reverse rotation of the driven member, and means for effecting transfer of the guide means from one of the track-ways to the other to effect shifting of the latch-dog into engagement with the engaging portions 20 of the driving member.

3. In combination with a rotatable driving member having latch-dog engaging portions, a 25 driven member including a sleeve-like body rotatably mounted on the driving member, a latch-dog movably supported on the driven member and adapted to engage the latch engaging portions on the driving member, a housing for said driven member and having inner and outer track-ways 30 interconnected by transfer-ways, a roller on the latch-dog operable in said track-ways to respectively maintain engagement of the latch-dog with the driving member during movement of the driven member by the driving member and disengagement of said dog during reverse movement of the driven member, means for effecting transfer of the roller from one of the track-ways to the other for shifting the latch-dog into engagement with the engaging portions of the driving 35 member, and means adapted for engagement by the roller to automatically disengage the latch-dog.

4. In combination with a rotatable driving member having latch-dog engaging portions, a 40 driven member including a sleeve-like body rotatably mounted on the driving member, a latch-dog movably supported on the driven member and adapted to engage the latch engaging portions on the driving member, a housing for said driven member, having inner and outer track-ways 45 interconnected by transfer-ways, guide means on the latch-dog operable in said ways to respectively maintain engagement of the latch-dog with the driving member during movement of the driven member by the driving member and disengagement therefrom during reverse movement of the driven member, means for effecting transfer of the guide means from one of the track-ways to the other for shifting the latch-dog into 50 engagement with the engaging portion of the driving member, means for engagement by the guide means to disengage the latch-dog, and a jerk line connected with the driven member, adapted to wind upon said driven member during driving thereof by the driving member and whereby the driven member is rotated reversely upon unwinding of the line.

5. In combination with a rotatable driving member having latch-dog engaging portions, a 55

driven member including a sleeve-like body rotatably mounted on the driving member, a latch-dog movably supported on the driven member and adapted to engage the latch engaging portions on the driving member, a housing for said driven member and having inner and outer track-ways interconnected by transfer-ways, a roller on the latch-dog operable in said ways to respectively maintain engagement and disengagement of the latch-dog with the driving member, means for effecting transfer of the roller from one of the grooves to the other to move said latch-dog into engaging relation with said engaging portions of the driving member, means engageable by the roller to disengage the latch-dog, and a jerk line connected with the latch-dog and adapted to be wound on the driven member when the latch-dog is engaged with the driving member and to be unwound from the driven member to return the driven member to its original position.

6. In combination with a driving member including a rotatable driving shaft, a quill sleeved on the shaft and having latch-dog engaging portions, means fixing the quill to the shaft, a driven member sleeved on the quill and having a circumferential opening, a jerk line, a latch-dog connected to the jerk line having a tail portion pivoted in said opening, said tail portion being

adapted to cooperate with the driven member to support the jerk line when the latch-dog is engaged with the quill, track-ways spaced at different distances from the driving member for maintaining engagement and disengagement of the latch-dog relatively to said engaging portions of the driving member, means for effecting engagement of the latch-dog with said engaging portions of the driving member to drive the driven member, and means for effecting automatic release of the latch-dog. 10

7. In combination with a rotatable driving member having latch-dog engaging portions, a driven member rotatable about the axis of the driving member, a latch-dog movably mounted on the driven member and adapted for engaging said engaging portions of the driving member, a member surrounding the driving member forming interconnected inner and outer track-ways, and a jerk line connected with the latch-dog 15 adapted to wind on the driven member, guide means on the latch-dog adapted for travel in one track-way when the latch-dog is engaged and in the other track-way when the latch-dog is disengaged, and means at the ends of the track-ways for shifting the guide means between the track-ways and the latch-dog to and from engagement with the driving member. 20 25

PHILIP M. REA.
